ATTORNEY

UNITED STATES PATENT OFFICE.

LLOYD R. HAMNER, OF GAINES, WEST VIRGINIA.

MAIL-BOX.

1,316,837.

Specification of Letters Patent. Patented Sept. 23, 1919.

Application filed November 21, 1916. Serial No. 132,635.

To all whom it may concern:

Be it known that I, LLOYD R. HAMNER, a citizen of the United States, residing at Gaines, in the county of Upshur and State 5 of West Virginia, have invented certain new and useful Improvements in Mail-Boxes, of which the following is a specification.

My invention relates to a letter or mail box and it aims to provide an improved 10 signaling means therefor which is movable to signaling position upon opening of the closure member of the box to avoid the necessity of operating a signal independently of the box, and a signal which will remain 15 in signaling position until manually moved out of such position regardless of subsequent operations of the said closure.

The above and additional objects, such as 20 will hereinafter appear, I attain by the construction illustrated in accompanying drawings, wherein:

Figure 1 is a side elevation of a mail box constructed in accordance with my invention, showing the closure opened and the signal 25 in signaling position;

Fig. 2 is a view similar to Fig. 1 but with the closure member closed and with the signal out of signaling position, and

Fig. 3 is a sectional view on the line 3—3 30 of Fig. 1.

Referring specifically to the drawings, wherein like reference characters designate like or similar parts, a suitable box or receptacle is provided at 4 having an opening 35 at one end which is normally closed by means of a closure 5 of any suitable construction, but in this instance being preferably provided with shields 6 at the sides thereof. Said closure is pivoted to the box by means 40 of a rod at 7.

A suitable signal 8 is employed which is adapted to serve as a signal to the postman that mail matter is within the box for collection, when the signal is in a vertical position. This signal has a staff or arm 9 pivoted at 10 to one side wall of the box and has a rivet or bolt 11 extending through its lower end and also through an elongated arcuate slot 12 provided in one side wall of 45 the box. Within the box, said pivot or bolt 11 also extends through an elongated slot 13 provided in a link 14 which is pivoted to one of the shields 6 as at 15.

Normally the parts are in the position

shown in Fig. 2 where the closure 5 is closed 55 and the signal 8 is lowered. When it is desired to deposit mail within the box, the closure 5 is pulled outwardly to the position shown in Fig. 1, and by this operation the link 14 is drawn forward, thus causing the 60 rear end of the slot 13 to engage with the lug 11, and raise the signal means to a vertical position as shown in Fig. 1. This is the position in which the signal functions to apprise the postman that matter is within 65 the box for collection. After depositing the mail matter within the box closure 5 may be closed or restored to the normal position and in moving to this position, due to the elongation of slot 13, link 14 will not move the 70 staff 9 and therefore the signal will remain in signaling position. The closure member can be freely operated also without disturbing the position of the signal until the signal is manually lowered to the position shown 75 in Fig. 2 and the link 14 will shift it upon the opening of the closure 5 as previously described.

Since merely the preferred embodiment has been illustrated and described, it is to 80 be understood that changes in the details of construction may be resorted to within the spirit and scope of the invention.

I claim:

1. In a deposit and collection receptacle, 85 a closure, a signal pivotally supported on the receptacle, said receptacle having an arcuate slot, a lug on said signal extending through said slot, inclosed means engaging said lug adapted to shift the signal upon 90 movement of the closure in one direction, and said means being provided with a slot to permit movement of the closure in the other direction without actuating the said signal. 95

2. In a deposit and collection receptacle, a closure, a link pivoted to the closure and disposed within the receptacle, said link having an elongated slot, the receptacle having an elongated slot, a signal pivoted exteriorly 100 of said receptacle, a lug extending through said signal and elongated slots.

In testimony whereof I affix my signature in presence of two witnesses.

LLOYD R. HAMNER.
